Des. 235,399
Patented June 17, 1975

235,399

CONTAINER FOR ROOTING PLANT CUTTINGS

Joyce Malnekoff, 1360 Sherwood,
Highland Park, Ill. 60035

Filed Jan. 4, 1974, Ser. No. 430,660

Term of patent 14 years

Int. Cl. D11—02

U.S. Cl. D6—113

FIG. 1 is a perspective view showing one side and the top of my design for a container for rooting plant cuttings.

FIG. 2 is a perspective view showing the opposite side and bottom of my new design.

I claim:

The ornamental design of a container for rooting plant cuttings, substantially as shown.
